UNITED STATES PATENT OFFICE.

GEORGE L. HUGHES, OF CHICAGO, ILLINOIS, ASSIGNOR OF ONE-HALF TO ROBERT E. COOPER, OF HOPKINSVILLE, KENTUCKY.

ELECTRIC SWITCH.

1,087,238.

Specification of Letters Patent. Patented Feb. 17, 1914.

Application filed November 18, 1912. Serial No. 732,090.

To all whom it may concern:

Be it known that I, GEORGE L. HUGHES, a citizen of the United States, residing at Chicago, in the county of Cook and State of Illinois, have invented certain new and useful Improvements in Electric Switches; and I do declare the following to be a full, clear, and exact description of the invention, such as will enable others skilled in the art to 10 which it appertains to make and use the same.

This invention relates to improvements in electric switches.

One object of the invention is to provide 15 an electric switch having a plurality of circuit closers adapted to be simultaneously operated to open and close a plurality of circuits.

Another object is to provide an electric 20 switch of this character having electrically operated means for closing the switch and means to automatically open the same, or a switch which may also be manually opened and closed.

With these and other objects in view, the 25 invention consists of certain novel features of construction, and the combination and arrangement of parts as will be more fully described and claimed.

In the accompanying drawings: Figure 1 30 is a plan view of my improved switch; Fig. 2 is a front view thereof; Fig. 3 is a cross sectional view through one end of the switch supporting frame; Fig. 4 is a plan view of 35 the switch supporting and operating mechanism; Fig. 5 is a detail perspective view of the supporting and operating means for the movable member of the switch; Fig. 6 is a similar view of the stop bracket for the movable member of the switch; Fig. 7 is an enlarged detail cross sectional view of the movable member of the switch illustrating two 40 of the contact terminals of one of the circuits closed by the switch.

My improved switch comprises a supporting frame 1 which is preferably of 45 rectangular shape and of suitable size, said frame having on one end an offset bracket plate 2 having a notch 3 adapted to receive a screw or other fastening device whereby 50 the frame may be secured to a suitable support.

Secured in the frame 1 adjacent to one side thereof is an electro-magnet 4 above 55 which and secured to the rear side of the

frame is a bracket 5 carrying the stationary terminal holding member 6 of the switch. Said member comprises an inner block or strip 7 of suitable non-conducting or insulating material to which are secured pairs of spring metal terminal plates 8, one above the other on opposite sides of the block 7 and held in position by upper and lower clamping plates 9 and 10 between which and the terminals 8 are arranged strips 11 of suitable non-conducting or insulating material. The clamping plates 9 and 10 and the strips 11 are fastened to the block 7 and the terminals 8 held in position by means of clamping screws 12 which are engaged with these parts as clearly shown in Fig. 1 of the drawing. The inner ends of each pair of terminals project a suitable distance beyond the inner edge of the block 7 and form spring contact fingers the extremities of which are bent inwardly and thence outwardly whereby the movable circuit closers of the switch may be readily engaged therewith as will be hereinafter more fully described. The opposite ends of the 80 terminals project a short distance beyond the outer edge of the block 7 and have secured thereto the wires of the circuit to be closed by these members.

Pivotedly mounted in the frame 1 is a 85 combined armature and supporting plate 13 for the circuit closers of the switch. The main portion of the plate 13 forms an armature 14 which is disposed opposite to and is adapted to be attracted by the magnet 4 90 when the latter is energized. The plate 13 is provided on its lower portion and at its opposite ends with right angularly formed right-angular bearing lugs 15 having therein tapered recesses 16 with which are adapted to be engaged the pointed inner ends of pivot screws 17 arranged in the opposite sides of the frame, and locking nuts 18 hold the screws in their adjusted positions. The plate 13 is provided on its ends with 95 upwardly extending arms 19 on the upper ends of which are right angularly outwardly extending lugs 20 to which are secured a block 21 of suitable non-conducting or insulating material carrying the movable circuit closing members of the switch. These are in the form of metal plates 22 which are arranged in pairs one above the other on the block 21 and opposite to the stationary terminals 8 with which they are adapted to be 100 105 110

engaged. The plates 22 have their inner ends bent inwardly but separated by a reduced inwardly extending portion 23 of the insulating block 21 whereby said inwardly bent ends of the plates are insulated from each other. The main portions of the plates 22 are secured to the block 21 by clamping plates 24 and screws 25 in the same manner as the terminals 8, and said plates have their outer ends projecting beyond the outer edge of the insulating block 21 and have secured thereto the wires of the circuits to be closed by the switch.

Formed on the lower portion of the plate 13 is a rearwardly projecting stop arm 26 which projects through a recess 27 formed in the outer side of the frame 1 and has its outer end disposed in position to engage a stop screw 28 mounted in a lug 29 on the lower end of a stop plate or bracket 30 which is suitably secured to the outer side of the frame 1 as shown. The screw 28 is adapted to be adjusted in the lug 29 to limit the outward swinging movement of the plate 13. When the magnet is deenergized this plate is automatically swung back to an inoperative position by a torsional spring 31 which is arranged in the frame 1 and has one end engaged with and secured to a right angularly formed lug 32 on the plate 13. The opposite end of the spring 31 is connected with the stem or pin 33 of an adjusting device which passes loosely through a slot in one end of the frame and is provided with a flat triangular head 34, the parts being of such construction that the head cannot rotate within the slot but the stem may, and hence the device may be drawn outward a trifle and turned to adjust the spring. By constructing my improved switch as herein shown and described it will be seen that any number of circuit closing members may be secured to the stationary and movable members of the switch, and will simultaneously close the various circuits connected therewith when the magnet 4 is energized to attract the armature plate 13 which will swing the movable member into position for engaging the plates 22 with the terminals 8. When the magnet is deenergized the circuits will be broken by the action of the spring 31 which will swing the armature plate and the parts carried thereby in a reverse direction.

While the switch has been herein shown and described as being automatically closed and opened by the magnet 4 and the spring 31 it is obvious that the switch may be manu-

ally operated by raising and lowering the arm 26 to bring the circuit closing members into and out of engagement.

From the foregoing description taken in connection with the accompanying drawings, the construction and operation of the invention will be readily understood without requiring a more extended explanation.

Various changes in the form, proportion and the minor details of construction may be resorted to without departing from the principle or sacrificing any of the advantages of the invention as claimed.

Having thus described my invention, what I claim is:

1. In an electric switch, the combination with a pair of elements adapted to be brought into contact, a frame supporting one of said elements and having a slot in one end, and an electro-magnet within said frame; of an armature pivoted in the frame and having arms supporting the other of said elements, a lug projecting from the armature substantially on a line between its pivots, a pin rotatably mounted through said slot in the frame and having a triangular head, and a spring connecting the pin with said lug, for the purpose set forth.

2. In an electric switch, the combination with a pair of spaced terminals having projecting inner ends, a pair of spaced plates having projecting inner ends adapted to pass between the inner ends of said terminals, a frame, a bracket therein rigidly supporting said terminals, and an electro-magnet within said frame; of an armature pivoted at its lower end within the frame and having upstanding arms with lugs at their upper ends, insulated connections between said lugs and plates, a spring connecting said armature and frame and drawing the former normally away from said electro-magnet, said frame having a recess in its outer side, a stop arm on the armature projecting through said recess, a plate on the outside of the frame having a lug at its lower end, and a screw adjustably inserted through said lug and adapted to limit the movement of said stop arm, for the purpose set forth.

In testimony whereof I have hereunto set my hand in presence of two subscribing witnesses.

GEORGE L. HUGHES.
